UNITED STATES PATENT OFFICE.

GEORGES ARBIN, OF BONDY, FRANCE, ASSIGNOR TO SOCIETE ARBIN FRÈRES & GUEUDRÉ, OF BRÉVANNES, FRANCE, A CORPORATION OF FRANCE.

MACHINE FOR SEWING MATS FOR HOTHOUSES AND THE LIKE.

1,413,511.

Specification of Letters Patent. Patented Apr. 18, 1922.

Application filed September 16, 1913. Serial No. 790,131.

(GRANTED UNDER THE PROVISIONS OF THE ACT OF MARCH 3, 1921, 41 STAT. L., 1313.)

To all whom it may concern:

Be it known that I, GEORGES ARBIN, a citizen of the Republic of France, residing at Bondy, France, have invented certain new and useful Improvements in Machines for Sewing Mats for Hothouses and the like; and do hereby declare the following to be a full, clear, and exact description of the invention, such as will enable others skilled in the art to which it appertains to make and use the same.

This invention relates to machines for sewing mats for use in hothouses and the like. The object is to provide a machine which may be employed instead of a loom, and which will replace the warp threads of the loom by several chain stitched seams spaced apart at suitable distances.

In the accompanying drawing—

20 Figure 1 is a front elevation of the machine, and

Figure 2 a side elevation.

The machine comprises a frame 1 provided with supporting legs. At the front of 25 the machine are arranged straps or endless belts 2 wound on pulleys 3, the spindles of which are supported by bearings 4 suitably secured to the frame 1. These belts are arranged in pairs, one of the belts of each 30 pair being above the other, as clearly shown in the drawing.

Below the upper belts 2, and toward the rear of the machine, are arranged endless chains 5 mounted in the extension of the 35 lower belts 2 and provided outside with points 6 slightly bent towards their ends.

To each end of the frame 1 is secured a vertical bracket 7, and these two brackets are connected together at different points of 40 their height by horizontal stays 8 on which are mounted supports 9 which can longitudinally move in the same and be secured in any desired position. Each of the said supports 9 terminates in front in a vertical 45 sleeve 10 forming a guide for a needle holder 11 similar to that of a sewing machine, and carrying at its lower end a needle 12.

The spools 13 carrying the thread are arranged on the upper stay 8 and are so 50 mounted as to permit the tension of the thread to be regulated. To that end, each spool 13 rests on a spring 14 surrounding the vertical pin 15 on which it can rotate, and

a nut 16 with a lock nut 17 are screwed on the upper screw-threaded end of the said 55 pin 15, which enables the spool to be pressed more or less strongly on the spring, for checking the movement of the spool.

Each thread passes through a thread guide 18 mounted on a corresponding support 9, 60 and through another thread guide 19 arranged at the upper portion of the needle holder 11, from which it descends vertically in order to pass through the eye of the 65 needle 2.

The frame 1 is provided with a driving spindle 20 to which is keyed a cam 21, and with the said cam engages a roller 22 mounted on a lever 23. The lever 23 is connected by means of a rod 24 to another 70 lever 25 carrying a pawl 26 intended to engage with the teeth of a ratchet wheel 27 keyed to the spindle 28 carrying one of the series of toothed pinions 29 on which are wound the chains 5. It will be seen that, 75 when owing to the action of the cam 21, the roller 22 is raised and lowered alternately with the lever 23, the lever 25 is given a similar movement, and the pawl 26 rotates the ratchet wheel 27 as well as the spindle 80 28 and the pinion 29 carried by the latter, in a given direction. The movement of rotation is transmitted to the other pinions 29 by the chains 5 themselves.

The spindle 20 carries a second cam 30 85 acting on a lever 31 keyed to a spindle 32 on which are mounted other levers 33 approximately arranged vertically and each terminating in a hook 34 forming a looper. Owing to the movement of the cam 30, the 90 levers 33 are given an oscillating motion, and the loopers 34 are reciprocated. These loopers are respectively arranged below tables 35 which in their turn are arranged opposite the needles 12.

To one of the ends of the spindle 20 is secured a lever 36 connected by a rod 37 to another lever 38 arranged on a spindle 39 mounted in the upper part of the machine and resting on the vertical supports 7. On 100 the spindle 39 are arranged other levers 40 which can be longitudinally moved on the same and secured each in a given position. Each of these levers is connected by a rod 41 to one of the needle-holders 11, and when 105 the lever 36 is rotated by the spindle 20,

it transmits by means of the rod 37 an oscillating motion to the lever 38 which, by means of the spindle 39, transmits a similar motion to the lever 40, which, by means of the rods 41, transmits a vertical reciprocating motion to the needle-holders 11. To the spindle 39 is keyed a balance weight lever 42 balancing the needle-holders 11.

The spindle 20 receives its movement from 10 a suitable line shaft by means of a belt, and is provided to that end at one of its ends with a fast pulley 43 and a loose pulley 44 which enables the machine to be started or stopped at will.

15 Above the chains 5 are arranged tables 45 with inclined planes, terminating at the back, near the space between the rolls 46 and 47 arranged above each other and mounted respectively on spindles 48 and 49 20 suitably supported by the frame of the machine. These rolls 46 and 47 can move longitudinally on their respective spindles and be secured to the latter in a given position. The upper spindle 48 is driven from the 25 spindle 20 by means of a chain 50 and toothed pinions 51 and 52 keyed respectively to the spindles 20 and 48; the bottom spindle 49 is driven by the spindle 48 by means of toothed pinions 53 and 54 keyed respectively to the said spindles. The pinion 54 is of a larger diameter than that of the pinion 53, for rotating roller 47 at a reduced speed compared with the upper roll 46. Finally, near the ends of the spindles carrying 35 the endless belts, are arranged circular knives 55 and 56, the position of which can be adjusted at will.

The straw to be sewn, to form the mats, is placed on the endless straps or belts 2, 40 between the pairs of which it passes in order to be brought to the chains 5, which distribute it in a uniform manner. The needles 12 are periodically lowered as explained, and the loopers 34 are operated for 45 making the stitches and for completing the seams. One seam may be in the middle of the mat and there may be one at each side.

The mat thus sewn is driven by the points 6 on the tables 45, and up the inclined planes 50 of these tables, in order that it may be released from points 6. It passes finally between the rolls 46 and 47 which drive it completely finished out of the machine, while the circular knives 55 and 56 cut the 55 straws at each side, so as to give the mat a uniform width.

With this machine it is possible to manufacture mats of various widths as the knives 55 and 56 as well as the needle-holders 11, 60 the loopers 34 and the other parts taking

part in the manufacture of the mat can be shifted, all these parts being adjustable. In the same way, the number of seams can be varied at will by arranging on the stays 8 a suitable number of needle-holders, and on 65 spindle 39 a corresponding number of levers 40 for operating the said needle-holders by means of connecting rods 41.

Having now particularly described and ascertained the nature of my said invention 70 and in what manner the same is to be performed, I declare that what I claim is:—

1. In a machine of the class described, a frame a plurality of conveying devices thereon, engaging devices carried by the 75 conveying devices, a table associated with each conveying device, arranged for elevating a mat and placing the same out of contact with the engaging devices, means for driving the conveying devices, a reciprocating needle-holding device, a reciprocating looping member beneath one end of each table, and single means for operating the looping member and the conveying devices. 80

2. In a machine of the class described, a 85 frame, a plurality of conveying devices carried thereby, engaging devices thereon, a table associated with each conveying device, arranged for elevating a mat out of engagement with the engaging devices, means for driving the conveying devices, means for mounting a needle above the conveying devices, and a looping member operated by the driving means and having one end disposed at the end of an adjacent table. 90

3. In a machine for sewing mats of straw, a traveling conveyer provided with points for receiving and conveying straws arranged transversely thereon, a lower endless band arranged to deliver straw sidewise to the 100 conveyer, a plurality of endless bands disposed above said lower band and adapted to cooperate therewith to carry straw between their adjacent plies, the receiving end of the lower band extending beyond the receiving end of the overlying bands and the delivery end of the latter overlying the receiving end of said conveyer, and sewing mechanism disposed in position to operate on the straw that is held between the conveyer and the delivery end of the upper bands. 105

In testimony whereof I have hereunto signed my name in the presence of the two subscribed witnesses.

GEORGES ARBIN.
